UNITED STATES PATENT OFFICE

PERCY GOTCH ROBINSON, THOMAS SHIRLEY FOWERAKER, HAROLD HOLMYARD
BEASLEY, AND TOM SARGENT, OF BRISTOL, ENGLAND

MEANS FOR TRANSFERRING DESIGNS TO PRINTING SURFACES

Application filed May 23, 1930, Serial No. 455,093, and in Great Britain June 11, 1927.

This invention relates to lithographic or other printing operations where an image (hereinafter referred to as "original") is transferred to a printing forme, and the invention is especially suitable for transferring a single design or a group of designs from a prepared lithographic stone or plate, letter-press plate, sketch or like on to another and usually larger plate of zinc, aluminum or the like, the single design or group of designs being transferred or offset on to the surface of the larger plate or may be repeated a number of times thereon, these offset or transferred impressions being capable of being spaced one from the other at predetermined distances.

More particularly the invention relates to machines for transferring designs to printing surfaces of the type wherein a cylindrical forme support has designs or the like transferred to it by the aid of rolling contact of one surface upon the other in the absence of gears for obtaining the relative transfer movement.

An aim of the invention is to provide improved means or devices adapted mechanically to transfer designs from an original with facility and accuracy to a printing forme in any desired predetermined relationship or repetition.

The present invention comprises apparatus for transferring designs to printing surfaces of the type described wherein the cylindrical forme support is pivotally mounted and is displaceable by the pivotal movement into contact with an original.

The original may comprise a plane surface adapted to be given a rectilinear displacement to cause rotation of the printing forme.

Further features of the invention will be hereinafter described and defined in the claims.

In the accompanying drawings illustrating a machine according to the invention:

Figure 1 is a front elevation,

Figure 2 is a corresponding plan,

Figure 3 is an end elevation to a larger scale, while

Figure 4 is an elevation of stop means for adjustment purposes.

In carrying the invention into effect according to one convenient mode as applied to the transfer of designs from an original having a reciprocating movement, directly to a printing cylinder or cylinder carrying a curved plate a bed or frame 4 is provided for the support of the original 5, which is adjustably mounted upon a carriage 6 supported upon the slides 7 of an intermediate carriage 8, which in turn is mounted upon the slides 9 of the frame 4.

The carriage 8 extends the full width of the machine between the supports or side frames 10 upon which the cylinder or forme 11 is pivotally mounted by the side levers 12. The carriage 6 and the original may thus be reciprocated parallel to the axis of the cylinder for stepping the design longitudinally thereof. Such movement of the original is effected by a lead screw 13, fine adjustment being controlled by the hand wheel 14, adapted to rotate the nut through the worm and worm wheel 15, 16. A graduated scale 17, with a hair-line device having a micrometer adjusting screw 18 is provided for indicating the axial position of the original.

Movement of the original 5 transverse to the forme cylinder 11 is effected by the chain and sprockets 19, 20 and hand wheel 21 or by any other convenient means.

The cylinder 11 is rotatably mounted in the side levers 12 and is provided with stops 22 for engagement with the jaw stop 23 carried also by the lever 12. Rotation of the cylinder is effected by the hand wheel 24 and gear wheel 25.

Pressure between the cylinder and original is obtained by connecting the frames or levers 12 by link 26 to the lever 27 mounted upon the shaft 28 carrying the weighted lever 29, the weight 30 of which forces the cylinder 11 down onto the original 5. The lifting of the cylinder is obtained by a pivoting of the weighted lever 29 by the hand lever 31, the arm 32 of which carries a roller 33 bearing upon one arm of the lever 29. The figure shows the parts in the non-contact position and by moving the hand lever 31 to the left, the weight becomes effective.

A counter-weight 38 is provided for balancing the cylinder 11.

In addition to the adjustable stop devices 22, 23 provided for limiting or setting the 5 rotary movement of the cylinder, stops may be provided for the reciprocating movement of the original.

The stops used in connection with the original 5 comprise projections 34 on the bed 8 10 which are adapted to engage adjustable stops 35 carried by plates and fixed in position by bolts engaging the undercut grooves 36 in the frame 4. The stops 35 are readily removable from the plates 37 so that should 15 it be necessary to move the original nearer to the cylinder the right-hand stop (see Figure 2) may be removed so that the corresponding projection 34 becomes inoperative and the bed 8 is brought to rest by the left-hand stop.

An alternative construction for determining longitudinal displacement of the original is shown in Figure 4; a stop bar 39 is provided and is carried in bearings 40 on the 25 carriage 8. The bar is provided with a number of longitudinal slots 41 in which adjustable stops 42 are located so that a plurality of series of stops is provided which are displaced along the bar as desired. The bar 30 is adapted to be rotated to bring the desired series of stops into position to be engaged by a pivoted indicator or pointer 43 which is carried upon the original support 6. The bar is prevented from rotating by a pivoted 35 catch 44 which engages in one of the slots 41. The pointer 43 is counterweighted so that it will be constrained to contact with a stop when in the vertical position and by reason of its pivoted support it will ride 40 over the stops, when relative longitudinal movement is imparted. Longitudinal displacement of the stop bar for a purpose hereinafter referred to may be effected by a hand wheel 45 having a screwed shank 46 which 45 operates in the nut 47 fixed in the bearing 40. Backlash is taken up by the spring 48. The periphery of the hand wheel is graduated and an indicator 49 provided so that the amount of longitudinal displacement of 50 the stop bar may be determined.

In operation the original is reciprocated inwardly towards the cylinder until one or other of the projections 34 engages the corresponding stop 35. The cylinder having 55 been rotated and set by the appropriate stop 22 is then displaced vertically into contact with the original which is then moved outwardly so that the cylinder rolls upon the original, receiving the impression in perfect 60 replica.

The operation may be repeated in order to transfer to the cylinder a series or group of designs in any desired spacing or contiguous relationship, or a group of superimposed designs spaced one from the other.

In this way the surface of the cylinder may be filled with the series or group of designs, when if it is so desired a second group or series of designs may be imposed upon the cylinder at any predetermined interval from the previous set or group or contiguous relationship by stepping the original axially into the required position.

In utilizing the apparatus for multi-colour or like work, one plate or form will be prepared for one colour or character of printing, while another or other plate or plates will be prepared for the other colours or characteristics. It will be appreciated that the disposition of the designs upon the various plates must be such that when utilized for printing purposes the designs on the various plates may be brought into accurate register. Owing, however, to unavoidable alterations which take place, such for example as the shrinkage or expansion of the paper, it is insufficient to transfer the design impressions corresponding with the various colours in exactly the same relative positions upon each plate. Allowance or accommodation must be provided for which corresponds with the distortion, shrinkage or other variation which may arise in the printing process. According to the invention in order to overcome the above defects and provide an apparatus in which actual colour printing registration may be effected, the axial displacement of the original may be provided with micrometer means or adjustments to allow for the deviations or distortions referred to above. For example, the hair-line device may be displaceable relatively to its mounting by a micrometer adjusting device 18.

Before stepping the original from one position to another in accordance with markings equivalent to the arrangement of the stops, the hair-line is displaced backwards or forwards by means of the micrometer adjustment to a degree predetermined according to the amount of shrinkage or contraction, for example, of the paper so that in moving from one situation to another the actual displacement of the original is not that which is represented between one mark and another but an increment or decrement of such displacement corresponding with the preliminary adjustment of the hair-line.

Alternatively, the bar or scale 17 used in conjunction with the hair-line may itself be displaceable by micrometer means to produce the same effect.

In order to take care of the registration circumferentially of the plate or cylinder, the stops 22 utilized to determine the position of the cylinder or forme may be individually adjustable circumferentially; or the stops 22 may be mounted upon a disc or bezel which is capable of relative angular adjustment with respect to the printing forme or the im-

pressions thereon so that the position of the stops as a whole may be adjusted.

The bed or carriage for the original 5 is provided with an upper part 50 capable of 5 rotational movement in a horizontal plane about the pivot 51 whereby the original may be rotated in order to alter the sense of the impressions transferred to the cylinder or forme. A pivoted catch 52 is provided on 10 the bed 6 adapted to co-operate with stops 53 on the upper part 50 whereby the latter may be locked to the bed 6 in either of the adjusted positions.

The initial adjustment of the original relatively to the bed 6 both laterally and vertically is effected by the screw-adjusting devices 54 which are associated with the upper part 50 and a carrier or box 55 in which the original is disposed.

20 In order to locate or register the position of the original initially a setting gauge 56 (see Figure 2) is provided comprising a sheet of plate glass or other suitable transparent material which is provided with a pair of 25 crossed hair-lines 57 or a transparency of the original design. The plate glass has a pair of ball-ended locating plugs adapted to seat within recesses in pillars 58 fixed upon the upper part 50 of the bed. The pillars are 30 fixed relatively to the pivotal axis 51 and by use of the gauge the original is correctly set relatively to such axis.

While the original described and illustrated comprises a plane reciprocating member, it is to be observed that a rotary or oscillatory original support as described with reference to Figure 7 of application Serial No. 281,835 may be provided.

Having now described our invention, what 40 we claim as new and desire to secure by Letters Patent is:—

1. Step and repeat apparatus for transferring designs to printing surfaces comprising a cylindrical printing forme adapted 45 to receive impressions from an original by the aid of rolling contact of one surface upon the other for obtaining the relative transfer movement, said forme being pivotally mounted and displaceable by the pivotal 50 movement into contact with the original.

2. Step and repeat apparatus for transferring designs to printing surfaces as claimed in claim 1 wherein the original comprises a plane surface adapted to be given a rectilinear displacement to cause rotation of the printing forme.

3. Step and repeat apparatus for transferring designs to printing surfaces as 60 claimed in claim 1 wherein the original comprises a plane surface adapted to be given a rectilinear displacement to cause rotation of the printing forme, and wherein the original is mounted for displacement parallel to the 65 axis of the printing forme for the purpose of

transferring the design axially of the printing forme.

4. Step and repeat apparatus for transferring designs to printing surfaces as 70 claimed in claim 1 wherein the printing forme is rotatably carried in a pivotally mounted frame associated with a weighted lever arranged to secure a mechanical advantage to create and maintain pressure for the 75 rolling contact.

5. Step and repeat apparatus for transferring designs to printing surfaces comprising a cylindrical printing forme adapted 80 to receive impressions from an original by the aid of rolling contact of one surface upon the other for obtaining the relative transfer movement, a pivotally mounted frame in which the printing forme is rotatably mounted, whereby the forme may be moved into or out of contact with the original, and stops for determining the position of the original design and the printing forme relatively to one another.

6. Step and repeat apparatus for transferring designs to printing surfaces as 85 claimed in claim 5 comprising a bed, a support for the original design slidingly mounted on said bed, a pair of projections on said sliding support and adjustable stops removably mounted on said bed and adapted to be engaged by said projections for the purposes set forth.

7. Step and repeat apparatus for transferring designs to printing surfaces as 90 claimed in claim 5 comprising a bed, a support for the original design slidingly mounted on said bed, a pair of projections on said sliding support and adjustable stops removably mounted on said bed and adapted to be engaged by said projections, and wherein the original design support is mounted for rotation about a vertical axis, and co-operating stops for holding said support with the design normal to the axis of the printing forme or at any other predetermined angle thereto.

8. Step and repeat apparatus for transferring designs to printing surfaces as 95 claimed in claim 5 comprising a bed, a support for the original design slidingly mounted on said bed, a pair of projections on said sliding support, adjustable stops removably mounted on said bed and adapted to be engaged by said projections, and a removable hair-line gauge for initially adjusting the design on said support, said gauge having projections adapted to engage in recesses in said support.

9. Step and repeat apparatus for transferring designs to printing surfaces comprising a cylindrical printing forme adapted 125 to receive impressions from an original by the aid of rolling contact of one surface upon the other for obtaining the relative transfer movement, a pivotally mounted 130

frame in which the printing forme is rotatably mounted whereby the forme may be moved into or out of contact with the original, a bed, a carriage slidably mounted on said bed, a support for the original adjustable with respect to said carriage in a direction parallel to the axis of the forme and stops for determining said axial position.

10. Step and repeat apparatus for transferring designs to printing surfaces as claimed in claim 9 wherein said stops comprise a pivoted pointer carried by the original support, a longitudinally slotted bar carried by the bed, and adjustable stops in said slot, the pointer being adapted to engage and override said stops.

11. Step and repeat apparatus for transferring designs to printing surfaces as claimed in claim 9 wherein said stops comprise a pivoted pointer carried by the original support, a bar mounted for rotation on the bed and having a plurality of longitudinally extending slots, and adjustable stops in said slots, the pointer being adapted to engage in a predetermined slot and engage and override said stops.

12. Step and repeat apparatus for transferring designs to printing surfaces as claimed in claim 9 wherein said stops comprise a pivoted pointer carried by the original support, a bar mounted for rotation on the bed and having a plurality of longitudinally extending slots, means for axial micrometer adjustment of the bar with respect to the bed, and adjustable stops in said slots, the pointer being adapted to engage in a predetermined slot and engage and override said stops.

13. Step and repeat apparatus for transferring designs to printing surfaces as claimed in claim 5 wherein a head is arranged at an end of the cylindrical forme, and cooperating stops on said head and the pivotally mounted frame.

45 14. Step and repeat apparatus for transferring designs to printing surfaces as claimed in claim 5, wherein heads are arranged at the ends of the cylindrical forme, adjustable stops carried by the heads, and 50 forked members pivotally mounted on the pivotally mounted frame and adapted to engage said stops.

In testimony whereof we have signed our names to this specification.
